(57) **CLAIM**

The ornamental design for a data logger, as shown and described.

DESCRIPTION

FIG. 1 is a front top perspective view of a data logger showing our new design;

FIG. 2 is a rear top perspective view thereof;

FIG. 3 is a front bottom perspective view thereof;

FIG. 4 is a rear bottom perspective view thereof;

FIG. 5 is a top plan view thereof;

FIG. 6 is a bottom plan view thereof;

FIG. 7 is a left elevational view thereof;

FIG. 8 is a right elevational view thereof;

FIG. 9 is a front elevational view thereof; and,

FIG. 10 is a rear elevational view thereof.

The broken lines shown in the drawings depicting protrusions, recesses and other features illustrate environment that forms no part of the claimed design.
